UNITED STATES PATENT OFFICE.

EDGAR MOTT BOTTOME, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A GLASS VESSEL.

44,352.

Specification for Design.

Patented July 22, 1913.

Application filed January 14, 1913. Serial No. 742,056. Term of patent 14 years.

To all whom it may concern:

Be it known that I, EDGAR MOTT BOTTOME, a citizen of the United States, and residing at Moundsville, in the county of Marshall and State of West Virginia, have invented a certain new, original, and ornamental Design for a Glass Vessel, in the accompanying drawing a superficially-ornamented glass vessel being shown.

No novelty is claimed herein for the shape of the vessel.

I claim:

The ornamental design for a glass vessel, as shown.

EDGAR MOTT BOTTOME.
